UNITED STATES PATENT OFFICE.

REIDAR G. SEEL, OF CHICAGO, ILLINOIS.

DISPENSING DEVICE FOR SAFETY MATCHES.

Application filed September 7, 1926. Serial No. 133,740.

This invention relates to a new and improved dispensing device for safety matches.

While it is well known that the common safety match is safer than the so-called parlor or kitchen match, in that the danger of accidental ignition thereof is reduced to the minimum, some objections to the use of these matches in kitchens have been raised due to the fact that in order to ignite the match, it must be struck on the friction surface of the box, thus requiring the use of both hands. This is sometimes inconvenient, particularly when a cooking utensil is held in one hand and it is desired to light the gas with the other. Inconvenience also sometimes arises due to the smaller number of matches in a box, as a fresh box must frequently be obtained from a source of supply often times at a distance.

20 The object of the present invention is, therefore, to provide a light and simple match dispensing device which may be manufactured at a low cost, adapted to hold boxes of safety matches so as readily to permit the removal of said boxes one by one and also to so hold a single box that the matches may be removed readily therefrom and struck on the friction surface provided on the edge of the box.

30 The present device is formed of but two pieces of pressed sheet metal joined together by providing projecting lugs or tongues at the edges of one section which are inserted through slots in the other section, the said lugs being then turned at right angles to secure the two parts together.

It is believed the further description of the device will be understood most readily from a detailed description thereof, taken in connection with the accompanying drawings, in which:

Fig. 1 is a face view of applicant's dispensing device, showing a box of matches mounted thereon;

45 Fig. 2 is a longitudinal section through the device of Fig. 1, and

Fig. 3 is a section on the line 3—3 of Fig. 1, looking in the direction of the arrow.

Referring now to the drawings in which like reference characters indicate the same parts in the several views, 10 represents a flat strip of sheet metal having the edges rebent, as indicated at 11 in Fig. 3. This expedient not only provides a smooth and rounded edge for the device, but also forms a rear surface for engagement with the wall

or other medium upon which the dispenser is mounted, within which lies the ends of the securing lugs, above referred to. The strip 10 is provided at the top and bottom with openings 12 and 13 adapted to receive screws, tacks, or other devices, by means of which the plate 10 may firmly be secured in position.

Secured to the plate 10 is a second sheet metal member 14 somewhat U-shaped in cross section, as disclosed in Fig. 3. The part 14 is provided on the edges thereof with the projecting lugs or tongues 15 which pass through slots 16 in the plate 10, the ends of said lugs being turned inwardly at the back of the plate at right angles, as clearly disclosed in Fig. 3, in order firmly to secure the two parts together.

The member 14 and plate 10 are arranged to provide therebetween a rectangular channel 16 adapted to receive a plurality of boxes 17 of safety matches. These boxes may be introduced into the channel 16 by merely inserting them in the top, and as the boxes are slightly smaller than the channel, they will thereupon drop by gravity to the bottom of the container. The outer face of the member 14, near the bottom thereof, is cut away for a distance slightly greater than the width of a match box, as indicated at 18 in Fig. 2. The sides of the member 14, co-extensive with the opening 18, are cut away as indicated by the dotted line 19 in Fig. 2, to permit the ends of the lowermost box 17 of matches to be grasped between the thumb and finger and withdrawn from its position, whereupon the whole column of match boxes will descend until the next box occupies the lowermost position. A part of the material cut away to provide the opening 18 is turned inwardly to 95 provide the bottom 20 upon which the column of match boxes rests.

The face of the section 14, above the cut away portion 18, has pressed therefrom the tongue 21, the upper end of which is turned outwardly, as indicated at 22. Upon withdrawing a box of matches from the channel 16, as described above, one end of the box may be placed in engagement with the portion 22 and the box forced downwardly so that the shell of the box is firmly grasped between the face of the part 14 and the tongue 21. The drawer 23 of the box, however, will be held against downward movement, thus causing the box shell or casing to move relative to the drawer so as to present the matches within the box in a position to be readily re-

5 moved and struck upon the friction surface 24 provided at the edge of the box. Thus it will be seen that the present device not only provides convenient storage space for a
10 store of five or more boxes of matches so arranged that the boxes may readily be withdrawn one by one, but further provides a mounting means for the boxes so that a match may be taken from the box and ignited on the friction surface thereof, thus avoiding the possible objections above referred to.

15 As the device herein disclosed is formed of but two pieces or strips of stamped or pressed sheet material, it may be manufactured very cheaply, yet provides a dispensing device of the maximum compactness, lightness and utility. The device herein disclosed will preferably be formed of sheet metal, but its manufacture is not limited to
20 the use of this material as other sheet material, such as fibre and the like may be substituted therefor with very satisfactory results. It, therefore, is to be understood that certain modifications in the dispenser herein disclosed are contemplated by the inventor. The protection therefor should be limited only by the scope of the appended claims.

25 Having thus described my invention, what I claim is new and desire to secure by Letters Patent of the United States is:

30 1. A match dispensing device comprising two strips of pressed or stamped sheet material, one of said strips being substantially flat or plane, the other said strip being generally U-shaped in cross section, tongues formed on the edges of the said U-shaped strip adapted to be received by slots in the plane strip whereby the said strips are secured together to form a channel therebe-

40 tween, the face of said U-shaped strip being cut away adjacent to the lower end thereof for a distance substantially equal to the width of a match box, a portion of said cut away portion being turned inwardly to form a bottom for the channel, and an upwardly directed resilient tongue pressed from the face of said U-shaped member above the cut away portion adapted to be received by the shell or casing of a match box, whereby the said box may be secured to the face of said 50 U-shaped member.

2. A match dispensing device comprising two strips of pressed or stamped sheet material, one of said strips being substantially flat or plane, the other said strip being generally U-shaped in cross section, tongues formed on the edges of the said U-shaped strip adapted to be received by slots in the plane strip whereby the said strips are secured together to form a channel therebetween adapted to receive a stack or column of match boxes, the face of said U-shaped strip being cut away adjacent to the lower end thereof for a distance substantially equal to the width of a match box, a portion of said cut away portion being turned inwardly to form a bottom for the channel, and an upwardly directed resilient tongue pressed from the face of said U-shaped member above the cut-away portion adapted to be received by the shell or 60 casing of a match box whereby the said box may be secured to the face of said U-shaped member, the upper end of said tongue being curved outwardly to form a support for the drawer of the box.

65 In testimony whereof I have signed this specification.

70 REIDAR G. SEEL.
